SWIMMING CAP

Walter Pierre Barnes, Chicago, Ill.

Application June 18, 1936, Serial No. 85,903

2 Claims. (Cl. 2—68)

This invention relates to improvements in swimming caps, and more particularly to caps made of rubber, rubberized fabric or some equivalent waterproof substance and placed over the head of a user when swimming, bathing, showering or the like to maintain the hair dry, although the invention may have other uses and purposes as will be apparent to one skilled in the art.

Heretofore, difficulty has been experienced in providing a bathing or swimming cap that is both attractive as well as efficient. This is especially true with female users, since in many instances caps that provide a pleasing appearance permit water to seep beneath the cap around the ears or adjacent the nape of the neck, where the hair is frequently piled the thickest when the cap is in position. This, of course, is highly objectionable, because only a relatively small portion of the hair need be wetted to ruin a coiffure.

I am aware that in an endeavor to solve such a problem, caps have been provided with a pneumatic tube, which may be inflated as desired, running around the rim of a cap, the tube either being fixed in position entirely around the rim or fixed at one point and clampable in position around the rim by the user. All of these caps of which I am aware were mainly of the bag type as distinguished from the tailored type which lies flat, one side upon the other, with the fold along a central seam when the cap is not in use.

Obviously, the tailored form of cap is the most desirable, because one of the major objects in providing a bathing cap for women is to style the cap so that it will not detract from the beauty of the user. A bathing cap having a pneumatic tube running entirely around the rim thereof is highly objectionable for the reason that, regardless of the smartness of the particular cap, the pneumatic tube which is on the inside of the cap will cause a bulge, and in the regions of the head where there is no hair, such as the forehead and temple regions, such a bulge gives the highly objectional appearance of the user being afflicted with a rather hideous cranial deformity. In addition, all caps made heretofore utilizing a pneumatic tube and of which I am aware had a tube or valve exposed in an unsightly manner, detracting materially from the attractiveness of the cap.

With the foregoing in mind, it is an object of the present invention to provide a bathing cap especially designed to prevent the entrance of water therebeneath and which also tightly and snugly fits the front part of the head of a user without any objectionable bulge or unsightly appearance.

Another object of the invention is the provision

of a bathing or swimming cap having the aforesaid features and which is made in the form of a tailored bathing cap of a character that will lie flat with the fold along a central seam when not in use.

It is also an object of this invention to provide a swimming cap having an inflatable portion near the edge of the cap extending over the ears, behind the ears and across the nape of the neck, but which terminates short of the forehead of the user, permitting the front portion of the cap to seat tightly against the forehead of the user.

Still another object of the invention is the provision of a swimming cap having an inflatable portion therein, the inflation of which is controlled by valve means, the structure of the cap being such that when in use, said valve means are concealed from the eye of an observer.

A further feature of the invention is the provision of a swimming cap of a tailored style, shaped to cover the ears of a user and provided with pneumatic or inflatable means at the sides and rear portions thereof which do not in any manner detract from the tailored appearance of the cap when in use.

Also a feature of this invention is the provision of a swimming cap having an inflatable portion substantially integrally formed therein, with the front portion of the cap being free of said inflatable portion so as to fit snugly against the forehead of the user.

While some of the more salient features, characteristics and advantages of the present invention have been above pointed out, others will become apparent from the disclosures hereinafter, taken in conjunction with the accompanying drawing, in which:

Figure 1 is an elevational view of a swimming cap embodying principles of the present invention, showing the same in position on the head of a user;

Figure 2 is an enlarged fragmentary sectional view, taken substantially as indicated by the line II—II of Figure 1, looking in the direction of the arrows;

Figure 3 is a transverse vertical sectional view, taken substantially as indicated by the line III—III of Figure 1; and

Figure 4 is a fragmentary exploded vertical sectional view, illustrating a modified form of construction.

As shown on the drawing:

In the illustrated embodiment of the present invention, there is seen a bathing cap made of rubber, rubberized fabric or equivalent water-

proof material. The cap comprises a body portion 5 having a depending part 6 on each side thereof to overlie the ears of a user, and being shaped in the forward portion, as indicated at 7, to expose the face and snugly fit the head. The cap is of the tailored style and when not in use will lie flat, one side upon the other, with the fold along the center rib 8. The cap is held upon the wearer's head with the aid of a chin strap 9 equipped near the end thereof with a buckle 10 for length-adjustment of the strap, and a suitable snap member 11 is carried by the buckle for engagement with a male snap member of a well-known character carried by the cap. The structure of the chin strap and buckle is best seen in the left hand part of Figure 4.

It will be noted that the front portion of the cap when it is properly disposed on the head of a user fits the forehead snugly, as indicated at 20 12, there being very little likelihood of seepage of water beneath the cap in this region, and the hair line is disposed a material distance from the edge of the cap. However, over and behind the ears and across the nape of the neck, there is 25 more danger of water seeping beneath the cap, and to prevent this, the cap is provided in this region with a pneumatic or inflatable portion 13, which is preferably continuous, extending substantially from the temple on one side, over the 30 ear, down behind the ear, across the nape of the neck, up behind the other ear, and over this ear to the opposite temple. Thus, it will be seen that the pneumatic portion is also shaped in keeping with the tailored shape of the cap and 35 is disposed in a region where the bulge created by the inflation of the pneumatic portion is offset by the mass of hair thereadjacent, so that there will be no unsightly appearance. With the cap fitting snugly over the forehead, which region of 40 the cap is free from the pneumatic portion, the cap will not in any manner detract from the appearance of the user and yet will be extremely efficient against seepage.

The pneumatic portion 13 may be either per- 45 manently inflated and sealed or it may be provided with a valve for selective inflation and deflation. In the present instance, the pneumatic portion 13 is preferably formed by vulcanizing or equivalently attaching a relatively thin strip 44 50 of impervious material, such as rubber, to the body portion 5 of the cap, as indicated at 15.

The strip 14 is so attached along its marginal edges, leaving the central portion rather loose to better accommodate inflation. With reference to Figure 1, it will be seen that the portion 13 may be selectively inflated or deflated through a valve element 16 which may be of any suitable or desirable construction.

In Figure 4, I have shown a slightly modified form of construction, wherein all of the previously described structure is present, but the valve 10 is positioned so as to underlie one of the snap elements 11 of the chin strap 9. The outer portion of the valve is shaped, as indicated at 17, in the manner of a male snap member, so that the snap 11 may engage the part 17, whereby 15 the valve is concealed by the end of the chin strap and so will not detract in any manner from the beauty of the cap.

From the foregoing, it is apparent that I have provided a bathing or swimming cap which may 20 be made in a tailored style, which effectively prevents leakage or seepage of water therebeneath, and which will not detract from the beauty or appearance of the user when worn. Further, the cap is economical to manufacture, durable 25 and may include an inflatable portion selectively inflatable or deflatable with no parts exposed in an unsightly manner when in use.

I am aware that many changes may be made and numerous details of construction may be 30 varied through a wide range without departing from the principles of this invention, and I, therefore do not purpose limiting the patent granted hereon otherwise than is necessitated by the prior art.

I claim as my invention:

1. As an article of manufacture, a swimming cap having an inflatable portion therein, a valve controlling the inflation of said portion, and a chin strap having a free end engageable over the 40 outer part of said valve to anchor the end of the strap and conceal the valve.

2. As an article of manufacture, a swimming cap having an inflatable portion therein, a snap member housing a valve controlling the inflation 45 of said portion, and a chin strap having a free part carrying a cooperative snap member for engagement with the first snap member to anchor the free part of the strap and conceal the valve.

WALTER PIERRE BARNES.
